Des. 215,175
Patented Sept. 9, 1969

215,175

LIGHTING CASING

Edwin F. Osborne, Jr., Houston, Tex., assignor to Esquire, Inc., New York, N.Y., a corporation of Delaware

Original design application Nov. 8, 1967, Ser. No. 9,331.
Divided and this application Mar. 1, 1968, Ser. No. 11,226

Term of patent 14 years

Int. Cl. D26—03

U.S. Cl. D48—20

FIGURE 1 is a rear perspective view of a lighting casing constructed in accordance with one embodiment of my design.

FIGURE 2 is a front perspective view of the lighting casing shown in FIGURE 1.

The support pole in broken lines in FIGURES 1 and 2 is shown for illustrative purposes only.

This application is a division of my copending application Ser. No. D. 9331, filed November 8, 1967.

I claim:

The ornamental design for a lighting casing, as shown and described.
